UNITED STATES PATENT OFFICE.

PHILIP COHN, OF NEW LAREDO, TAMAULIPAS, MEXICO.

MACHINE FOR EXTRACTING AND CLEANING THE FIBERS OF PLANTS.

SPECIFICATION forming part of Letters Patent No. 293,422, dated February 12, 1884.

Application filed June 6, 1883. (No model.)

To all whom it may concern:

Be it known that I, PHILIP COHN, of New Laredo, and State of Tamaulipas, Mexico, have invented a new and Improved Machine 5 for Extracting and Cleaning the Fibers of Plants, of which the following is a full, clear, and exact description.

My improved machine is intended for use in extracting the fibers of plants—such as maguey, 10 lechuguillas, ramie, &c.—and at the same time cleaning the said fibers.

The object of the invention is to break and scrape off the outside of the plants and the soft parts or meat of the inside, and this I accomplish by means of dull-edged knives arranged spirally upon a roller, that is fitted to revolve at a high rate of speed, as hereinafter described and claimed.

Reference is to be had to the accompanying 20 drawings, forming part of this specification, in which similar letters of reference indicate corresponding parts in all the figures.

Figure 1 is a side elevation of my improved machine. Fig. 2 is a longitudinal section of 25 the same, and Fig. 3 is a side elevation of one of the knife-rollers in larger size.

The mechanism is mounted upon a suitable frame, A, that is fitted at one end with a shaft, 30 a, for connection of power. b b are a pair of feed-rollers, and d d a similar pair of rollers, the lower roller of each pair carrying an endless belt or apron, c, for feeding material to the knives.

Forward of the rollers d d is a table, e, which 35 is preferably covered or surfaced with sole-leather, so as to prevent the material from slipping, and above the table is fitted a knife-roller, f, which is supported at its ends in boxes that are fitted to slide vertically; and g 40 are springs above the boxes for pressing the knife-roller into contact with the material on the table.

h is a presser-bar supported in a cross-bar, i, and fitted with a spring, k, which forces the 45 bar down upon the table e, for the purpose of holding the plant so it may not run away from the knife-roller, as hereinafter specified.

At the end of the table e is an endless traveling apron, l, carried by suitable rollers, and 50 passing beneath a drum or cylinder, m, around one side of which are arranged a series of

small rollers, n, extending from the forward end of the apron l to the upper side of the drum, where there is a second table, o, also covered with leather. Above this table o is a 55 knife-roller, f', and also a presser-bar, h'.

At the opposite end of the table o is a delivery-apron, p, carried by suitable rollers, for delivery of the clean material. The knife-rollers f and f', as shown most clearly in Fig. 60 3, are fitted with spiral blades or knives f², the edges of which are dull or blunt, so that they will act to scrape without cutting the fiber. The rollers carrying the apron e and the knife-roller f are driven by belts from a 65 pulley upon the shaft a, the pulley for the belt of the knife-roller being of considerable diameter, so as to give a rapid rotation to the roller. The upper knife-roller is driven by a cross-belt directly from a pulley on the shaft of the 70 lower roller, while the apron l, drum m, and rollers n are driven by a belt from a pulley on the lower roller b and gearing; but these connections may be made in any convenient manner.

The plant is fed to the two rollers b b from a suitable table or otherwise, and passes upon the apron e, which carries it forward to the second set of rollers, d d. These two pairs of rollers b d serve to crush or flatten the material, and the two upper rollers should be adjustably fitted, so that they can be raised or lowered to accommodate different thicknesses of plants. From the rollers d d the material 80 passes upon the table e beneath the presser h 85 and knife-roller. The presser prevents the material from being dragged forward by the knife-roller without the fiber being removed, and, being thus held, the knives on the knife-roller serve to scrape or clean the plants, and the 90 pressure of the springs g of the knife-roller is to be so regulated that the knives act to remove the skin and softer portions of the plant, thereby scraping the fiber bare. From the table e the material, thus cleaned upon one 95 side, then passes to the apron l, and is carried by the drum m and rollers n to the upper table, o, upon which it is laid in a reversed position, or with the cleaned side downward, so that the uncleaned portions are presented to 100 the second knife-roller, f', which acts in a similar manner to finish the cleaning operation,

so that the fiber is delivered in a completely separated and cleaned condition to the delivery-apron *p*, by which it is delivered to any suitable receptacle.

5 The machine acts most efficiently in the cleaning of fibrous plants for the removal of the useless or woody portions, and leaves the fibers in the best possible condition for subsequent use.

10 Having thus described my invention, I claim as new and desire to secure by Letters Patent—

1. The combination of the presser-bar *h*, the

spring-pressed roll *f*, having spiral blunt-edged blades *f*², and the table *e*, whereby the plants may be held sufficiently and scraped, as described.

2. The combination of the endless traveling apron *l*, the drum *m*, and the rollers *n*, whereby the plant may be carried from one table to the other and reversed in position, as described. 20

PHILIP COHN.
